ELECTRIC WIRING STAPLE

Raymond C. Marotz, 111 15th St., Clintonville, Wis.

Filed Oct. 1, 1965, Ser. No. 87,258

Term of patent 14 years

(Cl. D54—9)

Fig. 1

Fig. 2

Fig. 3

Fig. 4

Fig. 5

FIG. 1 is a perspective view of an electric wiring staple showing my new design;

FIG. 2 is an elevational view of said staple;

FIG. 3 is a top plan view;

FIG. 4 is a bottom plan view; and

FIG. 5 is an end view.

The end opposite from that shown in FIG. 5 is a duplicate thereof.

I claim:

The ornamental design for an electric wiring staple, as shown and described.
